FIG. 2

FIG. 1

FIG. 3

FIG. 4

FIGURE 1 is a side elevational view of a jug showing my new design;

FIGURE 2 is a top plan view thereof;

FIGURE 3 is the front elevational view thereof; and FIGURE 4 is the back elevational view thereof.

The side not shown is the same as the side shown. The characteristic features of this design reside in the configuration shown in full lines on the drawings.

I claim:

The ornamental design for a jug, substantially as shown and described.
